UNITED STATES PATENT OFFICE.

SAMUEL J. SHARP, OF WARWOOD, WEST VIRGINIA.

WATER-HEATER.

1,168,912.

Specification of Letters Patent. Patented Jan. 18, 1916.

Application filed June 16, 1915. Serial No. 34,480.

To all whom it may concern:

Be it known that I, SAMUEL J. SHARP, a citizen of the United States of America, and resident of Warwood, county of Ohio, 5 and State of West Virginia, have invented certain new and useful Improvements in Water-Heaters, of which the following is a specification.

This invention relates broadly to water 10 heating apparatus, and specifically to water heaters of that type employed for domestic purposes.

The primary object of the invention is to provide a water heater having a simple, 15 inexpensive and durable construction wherein the employment of the usual heating coil or coils is dispensed with and adapted to accomplish its heating function with a minimum of applied heat and, con- 20 sequently, with a minimum of fuel consumption.

A further object is to provide a device 25 of the character described all of the water passages of which are conveniently accessible, as for the removal of scale and sediment.

With these and other objects in view, the invention resides in the features of construction, arrangement of parts and combinations of elements which will hereinafter 30 be fully described, reference being had to the accompanying drawings, forming a part of this specification, in which—

Figure 1 is a perspective view of the invention with the face plate removed, showing 35 the water passages; Fig. 2 is a longitudinal section on the line 2—2, Fig. 1; Fig. 3 is an elevation of the invention with the back removed, showing the passages for 40 the products of combustion; Fig. 4 is a longitudinal section of the invention, taken on the line 4—4, Fig. 3; and Fig. 5 is a transverse section of the same, taken on the line 5—5, Fig. 3.

Referring to said drawings, in which 45 like designating characters distinguish like parts throughout the several views—A indicates generally a metal body, preferably of cast-iron and having a substantially rec- 50 tangular form in elevation. Said body comprises two parallel vertically disposed side-walls 1, an upper end-wall 2, and a vertical flat division wall 3, the latter ex- 55 tending from one of said side-walls to the other and being integral therewith. An encircling flange 4 is provided about said

body in a plane with the front edges of the side and end walls, the same being designed to have secured thereto, as by means of bolts 5, a cover or face-plate 6. Additional 60 securing bolts, as 5^a, may also be directed through said face plate into sockets 19 provided therefor in the adjacent face of said division wall 3, as shown. Said division wall 3 is located on a plane slightly to the 65 rear of the plane of the flange 4, there being thus constituted between said division wall and said face plate 6 a passage 7 of limited depth. Formed on the rear face of the division wall 3 is a plurality of substantially 70 rectangular box-like upwardly inclined receptacles 8 which open outward through said face plate, the interiors of said receptacles constituting water-receiving pockets 17. Said receptacles are disposed in stag- 75 gered relation, alternate receptacles being extended laterally from the opposite side walls 1. Each receptacle terminates at a distance from the side wall opposite that from which it is projected, there being thus 80 constituted between said receptacles at the rear of the division wall 3 a tortuous passage for the products of combustion, as is indicated by arrows in Fig. 3.

A back 9, preferably of sheet-metal, is 85 suitably attached, as by screws, to the rear edges of the side and end walls of the body, an asbestos board 10 being preferably interposed between said back and the passages inclosed thereby for the products of 90 combustion. Said back is extended at its lower end in curved form to provide a partial inclosure 11 for a gas burner 12 which may be of any suitable form or type.

As is obvious, heat emanating from the 95 burning gas ascends to a suitably located discharge passage 13 through the tortuous passage indicated by arrows in Fig. 3, being deflected back and forth by the receptacles 8. The walls of said receptacles and the flat 100 division wall 3 are effectually heated by direct contact therewith of the ascending products of combustion, and much of this heat is absorbed by the water which enters the lowermost of the pockets through a 105 suitably located passage, as 14, and thence passes outward over the face of the division wall, whence it follows a tortuous course, as indicated by arrows in Fig. 1, to a discharge passage 15 located in the upper end wall 2, 110 being deflected back and forth across said division wall and into the various pockets by

means of ribs 16 disposed along the upper edges of said pockets and having their outer edges in the plane of the outer edges of the side and end walls.

5 It will be apparent that a relatively large wall surface is presented for receiving heat and that both the heat and the water are so retarded in their passage that practically all of the former will be absorbed by the latter in its passage through the heater.

10 When the water passages become clogged with sediment or with excessive accumulations of lime, access may be readily had to the water passages by simply removing the 15 face-plate 6, whereupon a chisel or other tool may be conveniently used for removing said accumulations. As is obvious, therefore, no special skill is required to effect the cleaning of the heater.

20 A gasket 18 of suitable material is interposed between the flanges 4 and the face-plate 6 to prevent leakage.

What is claimed is—

25 1. In a water heater, a body portion having side walls, a vertical division wall extending from one side wall to the other and located adjacent to the front edges of said side walls; a back fixed on the rear edges of said side walls; a plurality of receptacles 30 extending rearward from said division wall toward the plane of said back, said receptacles opening outward through said division wall and constituting pockets; said division wall, back and receptacles being 35 relatively disposed to form a tortuous passage for heat; a face-plate mounted on the front edges of said side walls; said face-plate, division wall and pockets being relatively disposed to form a passage for water.

40 2. In a water heater, a body portion having side walls, a vertical division wall extending from one side wall to the other and located adjacent to the front edges of said side walls; a back fixed on the rear edges of said side walls; a plurality of receptacles 45 extending rearward from said division wall toward the plane of said back, said receptacles opening outward through said division wall and constituting pockets; said 50 receptacles being directed laterally from opposite side walls and being of less length than the distance between the latter; said division wall, back and receptacles forming an inclosed tortuous passage for heat; and a 55 face-plate mounted on the front edges of said side walls; said face-plate, division wall and pockets forming an inclosed passage for water.

60 3. In a water heater, a body portion having side walls, a vertical division wall extending from one side wall to the other and located adjacent to the front edges of said side walls; a back fixed on the rear edges of said side walls; a plurality of receptacles 65 extending rearward from said division wall toward the

plane of said back, said receptacles opening outward through said division wall and constituting pockets; said receptacles being directed laterally from opposite side walls and being of less length than the distance between the latter; said division wall, back and receptacles forming an inclosed tortuous passage for heat; a face-plate mounted on the front edge of said side walls; said face-plate, division wall and pockets forming an inclosed passage for water; and deflecting ribs formed on the front face of said division wall whereby said water passage is rendered tortuous.

70 4. In a water heater, a body portion having side walls, a vertical division wall extending from one side wall to the other and located adjacent to the front edges of said side walls; a back fixed on the rear edges of said side walls; a plurality of receptacles extending rearward from said division wall toward the plane of said back, said receptacles opening outward through said division wall and constituting pockets; said receptacles being upwardly inclined and being disposed in staggered relation; said division wall, back and receptacles forming an inclosed tortuous passage for heat; and a face-plate mounted on the front of said body; said face-plate, division wall and pockets forming an inclosed 75 passage for water.

80 5. In a water heater, a body portion having side walls, a vertical division wall extending from one side wall to the other and located adjacent to the front edges of said side walls; a back fixed on the rear edges of said side walls; a plurality of receptacles extending rearward from said division wall toward the plane of said back, said receptacles opening outward through said division wall and constituting pockets; said receptacles being upwardly inclined and being disposed in staggered relation; said division wall, back and receptacles forming an inclosed tortuous 85 passage for heat; a face-plate mounted on the front of said body; said face-plate, division wall and pockets forming an inclosed 90 passage for water; and deflecting ribs formed on the face of said division wall whereby said water passage is rendered tortuous.

95 6. A water heater comprising a burner, a cast iron body disposed over said burner, a back fixed on the rear face of said body, a face-plate fixed on the front face of said body, said body comprising a division wall located intermediate said back and said face plate; said division wall and back constituting walls of a passage for heat, and said division wall and face plate constituting walls of a passage for water; said division wall having rearwardly extending pockets formed therein which open into said water passage, and the walls of which render said heat passage tortuous.

100 7. A water heater comprising a burner, a 105

cast iron body disposed over said burner, a back fixed on the rear face of said body, a face-plate fixed on the front face of said body, said body comprising a division wall 5 located intermediate said back and said face plate; said division wall and back constituting walls of a passage for heat, and said division wall and face plate constituting walls of a passage for water; said division 10 wall having rearwardly extending pockets

formed therein which open into said water passage, and the walls of which render said heat passage tortuous; and means rendering said water passage tortuous.

In testimony whereof, I affix my signature 15 in presence of two subscribing witnesses.
